FIG. 1.

FIG. 2.

FIG. 4.

Inventor
Charles W. Armbrust
by May 11, 1917, at age.

UNITED STATES PATENT OFFICE.

CHARLES W. ARMBRUST, OF CHICAGO, ILLINOIS, ASSIGNEE, BY MESNE ASSIGNMENTS,
TO THE AMERICAN BRAKE SHOE & FOUNDRY COMPANY, OF WILMINGTON, DELA-
WARE, A CORPORATION OF DELAWARE.

BRAKE-SHOE.

1,239,445.

Specification of Letters Patent. Patented Sept. 11, 1917.

Original application filed February 19, 1916, Serial No. 79,237. Divided and this application filed April 17, 1916. Serial No. 91,623.

To all whom it may concern:

Be it known that I, CHARLES W. ARM-
BRUST, a citizen of the United States, resid-
ing at Chicago, in the county of Cook and
5 State of Illinois, have invented a certain new
and useful Improvement in Brake-Shoes,
of which the following is a full, clear, con-
cise, and exact description, reference being
had to the accompanying drawings, forming
10 a part of this specification.

My invention relates to brake shoes and
has for its object the provision of an im-
proved back for brake shoes which should be
simple in construction and easy of manufac-
15 ture.

My invention herein is a division of my
prior application Serial No. 79,237, filed Feb-
ruary 19, 1916.

My invention contemplates in its preferred
20 form the provision of a back for a brake shoe
having a key lug formed in sections, which
sections are separated.

I will explain several forms of carrying
out my invention more in detail by referring
25 to the accompanying drawing, in which—

Figure 1 is a top view of a back showing
one form of construction;

Fig. 2 is a perspective view showing the
back in its formed condition;

30 Fig. 3 is a top view of a blank showing a
modified form, and

Fig. 4 is a perspective view showing the
back of the modified form in its formed con-
dition.

35 Referring to Fig. 1, I show a blank from
which a back for a brake shoe is formed, this
blank having the body portion 3 provided
with holes 14, which holes 14 serve to permit
the metal of the shoe to pass therethrough
40 and securely bind the back and shoe together.
The fingers 15 also have cut-away portions
18, which cut-away portions, when these fin-
gers are bent into C-shape, aline to form
the key slot. An extending portion 19 of
45 these fingers remains horizontal, the fingers
being bent again at 20, and suitable holes 21
are again provided to permit of a substantial
union between the back and the shoe. The
fingers thus are bent upwardly at 16, extend
50 horizontally from the line 22 to the line 23,
extend vertically from the line 23 to the line
20, and then again extend horizontally. The
openings 18 aline to form the key lug. A

central strip 24 of the back remains intact
for strengthening purposes. Again it will 55
be seen that the back remains in its original
condition except that it is given the neces-
sary curvature.

In Figs. 3 and 4 I show a modified form of
the invention in which the fingers 15^a are 60
drawn from the body portion 3 at right
angles to the manner of drawing them in
Fig. 1.

From what has been described it is thought
the nature of my invention will be readily 65
clear to those skilled in the art. Having how-
ever thus described several forms which my
invention may take, what I claim as new and
desire to secure by Letters Patent is:

1. A back for a brake shoe provided with 70
a key lug, said key lug consisting of two
fingers formed out of the body of the back,
each forming a portion of said lug, and each
having two separated cut-away portions to
form a part of the key slot. 75

2. A back for a brake shoe provided with
a key lug, said key lug consisting of two op-
positely extending fingers formed out of the
body of the back, each forming a portion of
80 said lug and each having two separated cut
away portions to form a part of the key slot.

3. A back for a brake shoe having a key
lug formed of two fingers drawn longitudi-
nally from the body of the back, the material
between said fingers and on both sides there-
85 of forming three strips adapted to hold the
back and shoe together.

4. A back for a brake shoe consisting of a
body strip provided with a key lug consist-
ing of two longitudinal oppositely extending 90
fingers formed of continuous strips of metal
drawn longitudinally out of the body of said
back within the side edges thereof.

5. A back for a brake shoe provided with a
holding lug consisting of two oppositely ex-
tending fingers parallel with each other and
with the side edges of the back drawn longi-
tudinally out of the back without twisting. 95

6. A back for a brake shoe consisting of a
body strip having an integral lug divided 100
throughout longitudinally of said back.

7. A back for a brake shoe consisting of a
body strip having an integral continuous lug
separated throughout longitudinally of said
back. 105

8. A back for a brake shoe consisting of a

- body strip and having a sectional lug divided longitudinally of said back.
9. A brake shoe having a longitudinally slotted lug divided longitudinally of said back.
10. A back for a brake shoe provided with a key lug, said key lug consisting of two un-twisted fingers drawn longitudinally out of the body of the back without bending the remaining portions of said back.
11. A back for a brake shoe provided with a key lug, said key lug consisting of two oppositely extending un-twisted fingers drawn longitudinally out of the body of the back without bending the remaining portions of said back.
12. A back for a brake shoe provided with a key lug, said key lug consisting of two un-twisted fingers drawn longitudinally out of the body of the back, each forming a portion of said lug without bending the remaining portions of said back.
13. A back for a brake shoe provided with a key lug, said key lug consisting of two oppositely extending un-twisted fingers formed out of the body of the back, each forming a portion of said lug and extending longitudinally of said back.
14. A back for a brake shoe provided with a key lug, said key lug consisting of two fingers drawn longitudinally out of the body of the back between its outside edges.
15. A back for a brake shoe provided with a key lug, said key lug consisting of two fingers drawn longitudinally out of the body of the back without twisting said fingers.
16. A back for a brake shoe having a key lug formed of two oppositely extending un-twisted fingers drawn longitudinally out of the body of the back within its edges.
17. A back for a brake shoe, provided with two key lug sections forming oppositely extending fingers drawn longitudinally out of the back.
18. A back for a brake shoe having fingers stamped longitudinally from the body of the back to form a holding lug for said back.
19. A back for a brake shoe provided with a key lug formed of two parallel tongues drawn longitudinally out of said back.
20. A brake shoe back comprising a plate and two parallel un-twisted strips drawn longitudinally from the plate and arched between their ends to form a lug.
21. A brake shoe back comprising a plate and two strips drawn longitudinally from the plate within its edges and arched uniformly.
22. A brake shoe back comprising a plate, two strips drawn longitudinally from the plate within its side edges and arched in the direction of their length.
23. A brake shoe back comprising a plate and two strips drawn longitudinally from the plate and within its side edges and arched uniformly in the direction of their length and separated from each other.
24. A brake shoe back having two strips spaced from each other and from the side edges of the back and arched uniformly in the direction of their length.
25. A brake shoe back having a lug consisting of two uniform sections spaced apart and locked adjacent the side edges of the back.
26. A brake shoe back having a lug consisting of two uniform sections spaced from each other and from the side edges of the back.
27. A brake shoe back having two strips adjacent the sides thereof and arched uniformly lengthwise with the back.
28. A brake shoe back having two strips at the sides thereof arched to form a lug and provided with recesses therein for a keyway.
29. A brake shoe back having two strips, the sides thereof being arched to form a lug and provided with oppositely disposed recesses for the keyway.
30. A brake shoe back having two strips at the sides thereof arched to form a lug and an integral longitudinal extending strip between the arched strips.
31. A brake shoe back having two strips at the sides thereof arched to form a lug and an integral longitudinally extending strip between and below the arched strips to strengthen the back beneath the lug.

In witness whereof, I hereunto subscribe my name this 14th day of April, A. D. 1916. 100
CHARLES W. ARMBRUST.

Witnesses:

MAX W. ZABEL.
HAZEL A. JONES.
